BY

UNITED STATES PATENT OFFICE.

SAMUEL W. EVANS, JR., OF PHILADELPHIA, PENNSYLVANIA.

RETAINER FOR UMBRELLA OR PARASOL RUNNERS.

SPECIFICATION forming part of Letters Patent No. 363,615, dated May 24, 1887.

Application filed December 21, 1886. Serial No. 222,167. (No model.)

To all whom it may concern:

Be it known that I, SAMUEL W. EVANS, Jr., a citizen of the United States, residing in the city and county of Philadelphia, State of Pennsylvania,

5 have invented a new and useful Improvement in Retainers for Umbrella or Parasol Runners, which improvement is fully set forth in the following specification and accompanying drawings, in which—

10 Figure 1 represents a retainer secured to a stick of an umbrella in an open position. Fig. 2 represents a retainer secured to a stick of an umbrella for keeping the said umbrella in a closed position. Fig. 3 represents a front 15 end view of Fig. 2 inverted. Fig. 4 represents a section in line $x-x$, Fig. 2. Fig. 5 represents a side elevation of a modification. Fig. 6 represents a section of a modification.

Similar letters of reference indicate corresponding parts in the several figures.

20 My invention consists of a retainer for an umbrella or parasol runner formed of a spring-catch and a flanged plate which receives said catch and has the same connected with it, said plate filling the kerf in the stick in which the retainer is fitted.

Referring to the drawings, A represents part of the stick of an umbrella, (or parasol,) and B the runner thereof.

25 30 Formed in the stick, at places coincident with the position of the runner in the open and closed condition of the umbrella, are longitudinally-extending grooves or kerfs, and in the same are fitted the retainers for the runner. Each retainer consists of a plate, C, and spring-catch F, both formed of metal, the plate C of the lower retainer having flanges C' on its sides, forming somewhat of a chamber, within which the main portion of the 35 40 catch F is located. The catch in each retainer consists of a spring-shank, G, and a head, H, the end of the shank opposite to the head being firmly held by the plate, whereby said shank is elastic and moves when pressure is applied to the head, and returns to its normal position when said head is let go, it being noticed that the head extends partly beyond the walls of the plate C, and conse-

quently outside of the groove or kerf, so as to engage with the runner of the umbrella, 50 said runner being released by forcing in the head of the catch, as is evident.

It will be seen that the plates inclose the main portions of the catch and snugly occupy the kerfs of the stick flush with the surface 55 thereof, thus filling the same, their outer flanges closing the openings usually appearing in sticks of the class.

In Figs. 1 and 2 the ends of the shanks are held by lips a a, thrown up from the bodies of 60 the plates, said lips embracing the shanks.

In Fig. 5 the end of the shank is formed with a cross-head, b, which is retained by the flanges C' of the plate.

The plate C is preferably formed of sheet 65 metal, having its side turned up, forming the flanges C', between which the shank of the catch is located, said flanges and the plate proper occupying the kerf in the stick, guarding the catch, so that the latter is free to be 70 moved in opposite directions without actually coming in contact with the walls of the kerf. When the plate and catch are located in the kerf, the plate is prevented from displacement by means of pins driven through the stick and 75 plate.

Having thus described my invention, what I claim as new, and desire to secure by Letters Patent, is—

1. A retainer for an umbrella or parasol runner, consisting of a flanged plate and a spring-catch secured thereto at one end, and said plate with its flanges forming a chamber which receives the shank of the catch, substantially as described.

2. A retainer for an umbrella or parasol runner, consisting of a plate and a spring-catch secured thereto at one end, said plate having flanges at its sides, forming a chamber in said plate, the shank of the catch occupying said 90 chamber and being guarded by the flanges thereof, substantially as described.

S. W. EVANS, JR.
